UNITED STATES PATENT OFFICE.

ARTHUR SHELDON WELDY, OF CANTON, OHIO.

PUMP.

Application filed September 3, 1926. Serial No. 133,452.

My invention relates to pumps and particularly to rotating pumps in which the discharge therefrom may be accurately measured and regulated.

5 The objects of my invention are to provide a pump of this general character which may operate at comparatively high speed without noise or vibration; which is easily adjusted to compensate for the wear of certain elements therein; and which may be 10 regulated to accurately discharge at any predetermined rate between zero and its maximum capacity. Another object of my invention is to provide a pump in which the 15 action may be readily reversed without changing the direction of the drive, or which may be adjusted to operate in the same way regardless of the direction in which it is driven.

20 With these objects in view my invention includes the novel elements and combinations of elements described below and illustrated in the accompanying drawing in which—

25 Fig. 1 is a view of my pump in partial section along a plane containing the axis of rotation. It is a section in the plane 1—1 of Fig. 2;

30 Fig. 2 is a section of Fig. 1 in the broken planes 2—2;

Fig. 3 is an outside elevation of the cover plate for my pump on the side opposite the driving shaft;

35 Fig. 4 is a perspective view of the rotor or driving member;

Figs. 5 and 6 are views of the rotor and piston at oppositely disposed ends of the piston stroke; and

Fig. 7 is a modified form of piston.

40 Referring to the drawings, my pump comprises a housing formed of the annular ring, 1, and the cover plates, 2 and 3. The cover plate, 2, is secured to ring, 1, by cap screws, 4, and the cover plate, 3, which may herein- 45 after be referred to as the differential plate, is secured to ring, 1, by cap screws, 5. The cover plate, 2, is provided with a bearing, 6, adapted to receive the driving shaft, 7, which ordinarily would be connected to an 50 electric motor. The exterior end of this bearing is threaded, as shown at 40, to receive a nut (not shown) adapted to compress a packing about shaft, 7. The axis of shaft, 7, is substantially coincident with the 55 axis of ring, 1.

The inner side of plate, 3, is provided with a centrally disposed stub shaft, 8, adapted to carry the rotating, reciprocating piston or driven element, 9. The axis of this stub shaft, 8, when the device is assembled as shown in the drawings, lies in the same horizontal plane as the axis of shaft, 7, but is eccentric thereto in a horizontal direction, by the distance, 10, indicated in Fig. 2. In practice, I prefer to make this maximum eccentricity about $\frac{1}{16}$ of an inch, or, in other words, to provide a pump having a maximum stroke of about $\frac{1}{8}$ of an inch, as will be explained later.

Preferably integral with shaft, 7, is the 70 rotor or driving element, 11, cylindrical in shape, and recessed, as shown at 12, in Figs. 1 and 2, to receive the driven element, 9. A cover plate, 13, of the same diameter as the rotor, 11, is secured to the face of the rotor by means of screws, 14. This plate is provided with a circular opening, 15, in the center, and the inner face thereof is ground to a sliding fit with piston, 9. The periphery of the rotor, for a short distance in front of the plate, 13, is slightly smaller in diameter than the plate or other portion of the rotor, so that when the plate is secured in place, there is an annular recess, 16, formed between the plate and the rotor. Resting upon 80 the top half of the rotor is the cut-off gland, 17, preferably of brass. This gland is provided with the inwardly projecting ribs or lips, 18, which are adapted to a running fit in the recess, 16, between the rotor and cover plates, as shown in Fig. 1. The central inner part of the gland, 17, is provided with a recess, 19, which extends circumferentially about the inner part of the gland, 90 but which terminates at its extremities where inwardly extending projections, 20 and 21, are provided fitting closely against the bottom, 22, of the recess, 16. In other words, when the gland, 17, is in place, it covers about 180 degrees of the rotor surface 95 and the recess, 19, is closed at each end by contact of the projections, 20 and 21, with the bottom, 22, of the recess, 16. At the end of the gland, 17, which is shown at the right in Fig. 2 and which is angularly located about the rotor, 11, so that it will be substantially at the end of the pumping stroke of the piston, 9, is discharge pipe, 23, communicating with recess, 19, through the threaded hole, 24, and the deeper portion, 25,

100 105 110

of recess, 19. The pipe, 23, is bent in a semi-circle so as to clear rotor, 11, and the end, 26, thereof is threaded into the discharge opening, 27, in the ring, 1. The gland, 17, is held in contact with rotor, 11, by means of the adjusting screws, 28, 29 and 30, which are threaded through ring, 1, and are screwed down in contact with the outer periphery of the gland. These adjusting screws are covered and protected by the plugs, 39. To prevent the gland from rotating, the point of screw, 29, may be carried down into the gland, as shown at 31.

The holes, 32 (see Fig. 3), in the differential plate, 3, and through which pass the cap screws, 5, are slotted in a horizontal direction so that the differential plate, 3, carrying stub shaft, 8, may be moved toward or from the axis of the shaft, 7, thereby varying the eccentricity of the shafts.

The driven member, 9, is provided, as shown in Fig. 2, with a piston or radially projecting member, 33. This portion of the member, 9, does the actual pumping of the liquid and is accurately ground on the curvilinear surfaces, 34 and 35, to tangentially fit the sides, 36 and 37, of a slot, 38, in rotor, 11. This slot extends from the recess, 12, in the rotor to the cylindrical surface, 22, 30 forming the bottom of recess, 16.

In operating my device, oil, or other liquid to be pumped, is introduced into the interior of the housing through the opening, 36, in ring, 1. This oil fills the interior of the housing. As the rotor turns in the direction of the arrow shown in Figs. 2, 5 and 6, the piston, 33, of driven member, 9, will be reciprocated in the recess, 38, because the rotor will be turning about the axis of shaft, 7, as a center and the driven member will be rotating about the axis of stub shaft, 8, as a center. These axes are not coincident, and because of this eccentricity, the piston, 33, will move, outwardly and inwardly, each revolution of the rotor, a distance equal to twice the eccentricity of the shafts. When the device is assembled as shown in Fig. 2, it will be evident that the piston will be at the end of its discharging movement when the rotor is in the position shown in Fig. 6. As the rotor moves in the direction of the arrows from the position shown in Fig. 6 to the position shown in Fig. 5, the piston will be retracted in the recess, 38, and this recess, beyond the outer end of the piston, will become filled with the liquid from the casing. As the rotor moves in the direction of the arrows from the position shown in Fig. 5 to the position shown in Fig. 6, the piston will move outwardly forcing the small quantity of liquid in recess, 38, into the recess, 19, in gland, 17. The oil once delivered into gland, 17, cannot return to the casing because the gland is in close contact 65 with the rotor surface and the surface of the

cover, 13. As the gland becomes filled with liquid in this way, liquid will be forced outwardly through pipe, 23, communicating with the interior of the gland, and thus out of the discharge opening, 27, in the casing. 70

By loosening the cap screws, 5, and sliding the differential plate, the distance, 10, between the axes of shafts, 7 and 8, may be varied, producing a corresponding variation in the stroke of the piston and the discharge 75 of the pump. When the axes are coincident there will be no relative movement of the piston and rotor, and when (referring to Fig. 2) the axis of shaft, 8, is moved to the left of the axis of shaft, 7, the action of 80 the pump will be reversed unless the direction of rotation is changed.

In fabricating my device, the casing may be of cast iron, brass or the like, but to minimize wear, the piston should be of hardened 85 tool steel closely fitting the recess, 38, defined by the rotor, the surfaces, 36 and 37, and the cover plate, 13.

From a consideration of the foregoing, it will be apparent that the action of my pump may be reversed without reversing the direction of rotation. If desired, the cover plate, 3, may be shifted so that the axis of stub shaft, 8, will lie to the left of driving shaft, 7, instead of to the right, as shown in Fig. 95 2. In this case the pump will withdraw a liquid from recess, 19, in gland, 17, and discharge it into the casing, and liquid supplied through pipe, 23, will be forced out opening, 36. In like manner, should it appear desirable, the direction of rotation may be reversed without reversing the operation. 100

Where light, thin liquids are to be pumped, or, in other cases if desired, a two piece driven member of the general form 105 shown in Fig. 7 may be substituted for the piston, 9. In this case, the block, 41, which forms the piston proper, is accurately ground to fit the cylinder or chamber formed between the cover plate, 13, the rotor, 11, 110 and the surfaces, 36 and 37. This block is bored to receive the cylindrical end, 42, of the member, 43, which acts as a wrist pin in block 41. To provide for the slight oscillating movement of the block on the wrist pin, 115 the sides of the opening from the bottom of the block (when in the position shown in Fig. 7) are slightly beveled, as shown at 44.

While I have described the details of my 120 device in its preferred forms, it is to be understood that the words which I have used are words of description rather than words of limitation, and that changes, within the purview of the appended claims, may be 125 made without departing from the true scope and spirit of my invention in its broadest aspects.

What I claim is—

1. A pump comprising a casing, closely 130

interfitting members rotatively mounted independent of and eccentric to each other within said casing and forming a pumping unit comprising a cylinder and plunger 5 adapted to reciprocate therein, means for varying the relative reciprocating movement of said members, and means separate from said casing in contact with one of said members adapted to receive the discharge 10 of said unit.

2. A pump comprising a casing, closely interfitting members rotatively mounted independent of and eccentric to each other within said casing and forming a pumping 15 unit comprising a cylinder and plunger adapted to reciprocate therein, means in contact with one of said members adapted to receive the discharge of said unit, and means for adjusting the contact pressure between 20 said member and said receiving means.

3. A pump comprising a casing, closely interfitting members rotatively mounted independent of and eccentric to each other within said casing and forming a pumping 25 unit comprising a cylinder and plunger adapted to reciprocate therein, means for varying the relative reciprocating movement of said members, means in contact with one of said members adapted to receive 30 the discharge of said unit, and means for adjusting the contact pressure between said member and the receiving means.

4. A pump comprising a casing, a cylindrical driving member mounted to rotate 35 therein, a driven member rotatively mounted eccentric to and adapted to reciprocate radially within the driving member, a gland member closely fitting the periphery of the driven member, and means for adjusting the contact pressure between the driving 40 member and the gland.

5. A pump comprising a casing, a cylindrical driving member mounted to rotate 45 therein, a driven member rotatively mounted eccentric to and adapted to reciprocate radially within the driving member, a gland element closely fitting the periphery of the driven member, means for adjusting the contact pressure between the driving member 50 and the gland, and means for varying the eccentricity of the driving and driven members.

6. In a pump of the character described, the combination with a casing, of closely 55 interfitting members rotatively mounted independent of and eccentric to each other within said casing and forming a pumping unit comprising a cylinder and plunger adapted to discharge outwardly from the axis of rotation, and a gland element separate from said casing in contact with one

of said members adapted to receive the discharge of said unit.

7. In a pump of the character described, the combination with a casing, of a cylindrical driving member mounted to rotate therein, a driven member eccentrically mounted to reciprocate radially within the driving member, and a gland element separate from said casing closely fitting the periphery of the driving member within the zone of outward radial movement of the driven member to effect a cut off between the source of liquid supply and the discharge receiver. 70

8. In a pump of the character described, the combination with a casing, of a driving member axially mounted therein, a driven member axially mounted independent of but having a radial portion closely interfitting 80 and forming a plunger adapted to reciprocate within said last mentioned member, and a sliding cover plate for said casing carrying the axial mounting for the driven member and adapted to be moved relative to said 85 casing to vary the relative movement of said members.

9. In a pump of the character described, relatively reciprocating elements rotatively mounted independent of and eccentric to 90 each other, and closely interfitting along opposed, substantially tangential surfaces parallel to the axes of rotation; whereby said elements may oscillate slightly in respect to each other during the reciprocating 95 movement.

10. In a pump comprising a rotor provided with a rectangular passage therein, a plunger element closely fitted and adapted to reciprocate in said passage and having 100 curved surfaces tangential to opposite sides of said passage whereby said plunger may oscillate relative to said rotor during the reciprocating movement.

11. In a pump of the character described, relatively reciprocating elements rotatively mounted independent of and eccentric to each other, and closely interfitting along substantially tangential surfaces; whereby 110 said elements may oscillate in respect to each other during the reciprocating movement.

12. In a pump of the character described, the combination with a casing, of a rotating element therein forming the cylinder of said pump, a piston element adapted to be positively reciprocated in said cylinder, and a gland element separate from said casing and in contact with the cylinder forming element adapted to effect a cut off between the intake and discharge strokes of said pump. 115

ARTHUR SHELDON WELDY.
